UNITED STATES PATENT OFFICE.

LOUIS L. PATTERSON, OF CHICAGO, ILLINOIS.

INTERNAL-COMBUSTION ENGINE VAPORIZING ATTACHMENT.

Application filed December 9, 1921. Serial No. 521,097.

To all whom it may concern:

Be it known that I, LOUIS L. PATTERSON, a citizen of the United States, and a resident of Chicago, Cook County, Illinois, have invented a certain new and useful Improvement in Internal-Combustion Engine Vaporizing Attachments, of which the following is a specification.

This invention relates to internal combustion engines, and more particularly to the means employed for supplying the fuel thereto. As is well known, it has been proposed to collect the liquid fuel precipitated in the intake manifold, and to vaporize this liquid fuel and again discharge it into the intake manifold, so that the heavy oil thus collected will be saved and used as fuel for the engine, and whereby the heavy oil thus precipitated from the fuel mixture will be prevented from entering the engine. However, the means proposed for this purpose have necessitated the building of a special form of manifold, and the provision of some other special means.

Generally stated, therefore, the object of the invention is to provide an improved construction and arrangement whereby a heater for this purpose, adapted to be heated by the exhaust from the engine, thereby to vaporize heavy oil or liquid fuel collected from the intake manifold, may be applied to an engine having an ordinary manifold construction, thus obviating the necessity of building a specially designed manifold for the engine, and permitting the invention to be applied as an attachment to an engine having the usual or ordinary manifold construction.

It is also an object to provide certain details and features of construction and combinations tending to increase the general efficiency and the desirability of an attachment of this particular character for vaporizing the liquid fuel which is precipitated from the fuel mixture before entering the engine and for discharging the fuel thus vaporized into the intake manifold of the engine.

To these and other useful ends, the invention consists of matters hereinafter set forth and claimed and shown in the accompanying drawings, which are illustrative of one form of the invention and in which,

Fig. 1 is a front elevation of a vaporizing attachment embodying the principles of the

invention, showing the method of attaching the device to the manifold construction of the kind found on an ordinary internal combustion engine, the construction being illustrated for an engine having only two cylinders, and it being understood that the invention is applicable to any number of cylinders and to engines of different kinds without departing from the spirit of the invention.

Fig. 2 is an enlarged detail sectional view showing one of the collecting means or traps which are interposed between the intake manifold and the engine to collect the precipitated liquid fuel before it enters the engine.

Fig. 3 is a horizontal section on line 3-3 in Fig. 1.

Fig. 4 is a vertical section on line 4-4 in Fig. 1.

As thus illustrated, the engine 1, of which only a fragment is shown, may be of any suitable, known or approved construction. The intake manifold 2 is shown as being suitable for an engine having two cylinders, and the exhaust manifold 3 is accordingly designed for two cylinders, but it will be understood, as previously stated, that this is merely for convenience of illustration, and that the invention is applicable to any number of cylinders. In order, therefore, that the invention may be applied as an attachment to an engine having an ordinary manifold construction, thus obviating the necessity of changing or designing a specially formed manifold construction, means are interposed between the engine 1 and the ends 4 of the intake manifold to collect the liquid fuel before it has passed into the engine. For this purpose, therefore, the manifold is simply taken off and set out a distance from the engine, and the heads 5 are placed in position as shown, thus spacing the manifold from the engine; these heads being flat and ring-like in form and grooved inside at 6, and provided on their lower sides with depending portions 7 for connection with the tubes 8 which feed the liquid fuel to the heater 9, which forms a part of the invention.

The sheet-metal elements, such as the one shown in Fig. 2, are interposed in each joint thus formed between the engine and the intake manifold, each of said sheet-metal elements having a vertical retaining flange 10 which is clamped by the head 5 to

the engine, and having a contracted tubular portion 11 which extends through the head 5 and into or approximately to the adjacent end of the intake manifold, so that the 5 groove 6 forms a trap for collecting the liquid fuel which is precipitated from the fuel mixture before entering the engine. It is found, by the way of explanation, that the maximum point of precipitation, the 10 point where the liquid fuel is most liable to collect, is just where the intake manifold turns to enter the engine, and the invention, it will be seen, is designed with reference to this. The heater 9 is cylindrical in form, 15 and has its axis horizontally disposed, but is provided with a threaded boss 12 which is screwed into the lower portion or riser 13 of the intake manifold. Said heater is formed with an inner chamber 14, and with 20 an outer exhaust chamber 15, passages 16 extending through the outer chamber from the tube 8 to discharge the collected liquid fuel into the inner chamber 14, where it is then vaporized.

25 The outer end of the vaporizing chamber 14 has a closure in the form of a screw-threaded plug 17, the outer end of the chamber 15 has a screw cap 18 which permits access to the exhaust chamber. In applying 30 the invention to an ordinary manifold construction, a hole is tapped into the exhaust manifold 3, and a screw-threaded connection 20 is inserted therein. The top of the heater 9 has a boss 21, and this is connected by a 35 pipe 22 with the elbow connection 20, this pipe being held in place in a suitable or desired manner, as by cotter pins 23 and 24 to facilitate connection and disconnection when such is necessary or desirable. The 40 heater has a boss 25 on the lower side thereof for the pipe 26 by which the exhaust is discharged.

45 From the foregoing it will be seen that exhaust passes through the chamber 15 and thereby heats the chamber 14 to the desired temperature for vaporizing heavy oil or liquid fuel. The traps formed in part by the 50 grooves 6 catch the heavy oil or precipitated liquid fuel, and the liquid thus collected flows downwardly through the stems 7 of the head 5 and through the tubes 8 to the vaporizing chamber 14 of the heater. The liquid fuel 55 thus collected is vaporized and discharged through the connection 12 into the intake manifold 2, and is then allowed to pass into the engine. Thus a large part of the fuel that is ordinarily wasted is saved, and in addition heavy oil and liquid is prevented from entering the engine, thus very obviously securing 60 better results in the operation of the engine.

The vaporizing attachment can be taken off, if it becomes desirable not to use it, by removing the traps from between the intake 65 manifold and the engine, and by disconnect-

ing the exhaust connection 20 from the exhaust manifold, and by unscrewing the boss 12 from the intake manifold. Screw plugs can then be inserted in the threaded holes thus formed in the two manifolds, and in 70 that way the manifold construction will be practically the same as it was before the invention was applied thereto. It will be understood that the intake manifold 2 is supported on the engine in any suitable or desired manner, so that the heads 5 and the flanges 10 are clamped tightly in place, thus 75 providing tight joints at these points.

When the attachment is in use, the plug 17 can be removed to permit access to the chamber 14 for the purpose of priming the engine, if necessary or desirable, in a manner that will be readily understood. The exhaust chamber 15 can be cleaned by removing the screw cap 18 to permit access thereto. 85 Thus the two closures are concentric to the axis of the cylindrical heater.

What I claim as my invention is:

1. In combination with an internal combustion engine having an intake manifold 90 and an exhaust manifold, a heater to vaporize liquid fuel, means interposed between the engine and the intake manifold to collect the liquid fuel, means to feed the liquid fuel from said collecting means to said heater, a 95 connection from the exhaust manifold to said heater, and a connection to discharge the vaporized fuel from said heater into said intake manifold.

2. A structure as specified in claim 1, said collecting means comprising a trap formed with a head for insertion between the intake manifold and the engine, and with a depending feed tube connection, so that the heater 100 may be applied to an engine having an ordinary manifold construction.

3. A structure as specified in claim 1, comprising a sheet metal element disposed in the joint between the engine and the intake manifold and forming part of said collecting 110 means.

4. A structure as specified in claim 1, said heater being screwed into the intake manifold, and said exhaust connection being tapped into the exhaust manifold, so that 115 the heater is applicable to an engine having an ordinary manifold construction.

5. In combination with an internal combustion engine having a manifold construction therefor, a heater to vaporize liquid fuel 120 collected or precipitated from the fuel mixture before passing into the engine from the intake manifold, connections for feeding the collected liquid to the heater, a connection for discharging the vaporized liquid from the heater into the intake manifold, and a connection for utilizing the exhaust to heat said vaporizing heater, all forming an attachment which is readily removable in its 125 entirety from the manifold construction, so 130

that the manifold may be used either with or without the attachment.

6. In combination with an internal combustion engine having an intake manifold and an exhaust manifold, means interposed between the engine and the intake manifold to collect the liquid fuel, spacing the manifold a distance from the engine, means to feed the liquid fuel from said collecting means, and a receptacle to receive the liquid from said feeding means.
7. A structure as specified in claim 6, said spacing and collecting means comprising a
- trap formed with a head for insertion between the intake manifold and the engine, and with a depending feed tube connection, so that the collecting means may be applied to an engine having an ordinary manifold construction.

8. A structure as specified in claim 6, comprising a sheet metal element disposed in the joint between the engine and the intake manifold and forming part of said collecting means.

LOUIS L. PATTERSON.
